UNITED STATES PATENT OFFICE.

GEORGE M. SCHEBLER, OF INDIANAPOLIS, INDIANA, ASSIGNEE TO FRANK H. WHEELER, OF INDIANAPOLIS, INDIANA.

CARBURETER.

1,108,245.

Specification of Letters Patent. Patented Aug. 25, 1914.

Application filed March 21, 1912. Serial No. 685,252.

To all whom it may concern:

Be it known that I, GEORGE M. SCHEBLER, a citizen of the United States, residing at Indianapolis, in the county of Marion and State of Indiana, have invented a new and useful Carbureter, of which the following is a specification.

The object of my invention is to provide a carbureter capable of delivering various 10 volumes of carbureted air of substantially uniform quality.

The accompanying drawings illustrate my invention.

Figure 1 is a vertical axial section, and 15 Fig. 2 a horizontal section on line 2—2 of Fig. 1.

In the drawings, 10 indicates the main body of the carbureter provided with a horizontal flange 11 and a depending tubular 20 stem 12 through which a primary air inlet passage 13 is formed. The stem 12 near its lower end is provided with a circumferential flange 14 and the lower end is projected through an opening 15 in the bottom of the 25 reservoir bowl 16, a packing 17 being introduced between the bottom of the bowl and the flange 14, and a nut 18 serving to clamp the bowl in place upon the stem 12 and to bring the upper end of the bowl into contact with the lower face of the flange 11. A primary air supply passage 19 is interposed between nut 18 and the bottom of bowl 16, as shown.

In the lower end of stem 12 is formed a 35 fuel sump 21, the lower end of which is closed by a removable plug 22, and this sump is supplied with fuel through passages 23 which extend through the wall of stem 12. Above the lower ends of the supply passage 40 23 is a partition 24 which is bored and threaded to receive the fuel nozzle 25 which projects upwardly into the primary air passage 13. This nozzle might be provided with a needle valve projected downwardly 45 through sump 21 and plug 22 but I prefer to properly proportion the outlet of nozzle 25 relative to the cross section of passage 13 so as to insure a proper mixture of fuel and air within this tube without the necessity of 50 an adjustable valve.

In fact it is one of the objects of my in-

vention to produce a carbureter structure which, so far as the fuel nozzles are concerned, may be properly proportioned in the factory and so that this proper proportioning cannot be interfered with by persons whose presumption exceeds their knowledge.

The primary air inlet 13 discharges directly into the main mixture passage 26, being preferably in alignment with this passage, and in this passage I mount the usual throttle valve 27.

Leading into the side of the passage 26 above the delivery end of passage 13 are several supplementary mixture delivery passages 28, each of which discharges from a valve chamber 29. Delivering into each valve chamber 29 is a supplemental air inlet passage 31, a valve seat 32 being interposed between each passage 31 and its adjacent chamber 29. Arranged adjacent each valve seat 32 is a supplementary delivery nozzle 33 which is connected to a tube 34, the lower end of which depends into the bowl 16 a sufficient distance to be constantly submerged by the fuel within the bowl. As it is convenient and desirable that the nozzles 33 be materially above the normal level of fuel within bowl 16, the bores of tubes 34 are so proportioned as to have sufficient capillary 75 attraction for the fuel to permit a normal maintenance of fuel level substantially at the delivery end of nozzle 33. Seated upon each valve seat 32 is a valve 35 which is held to its seat by a spring 36, the force of which 80 upon the valve may be readily adjusted by means of a screw plug abutment 37 threaded into the outer end of chamber 29 and held in adjusted position by means of a spring detent 38. Each plug 37 is axially bored at 90 39 to form a guide and holder for the stem of the adjacent valve 35.

The main body 10 is provided with a secondary air supply passage 41 which leads into passage 26 above the delivery end of 95 passage 13 and substantially opposite the supplemental passages 28. The inlet end of passage 41 is provided with a valve seat 42 upon which is seated an inwardly opening valve 43 yieldingly held to its seat by a 100 spring 44 which abuts against a collar 45 sleeved upon a pin 46 which is supported

by the main body 10 and projected upwardly into the axial bore 47 of valve 43. The normal effect of spring 44 is such that the valve 43 will yield more and more as the vacuum 5 within the passage 26 is increased; this movement being properly proportioned to deliver to passage 26 requisite amounts of diluting air depending upon the number of carbureting units delivering at any particular time to the mixture passage 26.

Under many weather conditions it is desirable, at the starting of the apparatus, that the delivered mixture be richer than will be desired when the motor has become heated, 15 and for that purpose I journal a rock shaft 51 in the main body 10 and provide it at its inner end with a crank pin 52 carrying a roller 53 which roller engages collar 45 in such manner as to shift it axially upon pin 20 46 and thus vary the compression of spring 44. Shaft 51 may be rocked by any suitable means, as through a lever 54 carried upon its outer end.

In practice, the several abutments 37 will 25 be individually adjusted so that, as the speed of the engine increases, and the demand upon the mixture passage 26 correspondingly increases, the valves 35 will yield successively from their seats so that the supply 30 of fuel mixture will be successively augmented automatically, each carbureting unit, however, operating in a fixed and uniform manner.

By the arrangement shown, I have succeeded 35 in producing a multi-unit carbureter which is very compact and practically no larger than the single unit carbureters now commonly in use. The level of fuel within 40 the bowl 16 will be normally and automatically maintained in the usual manner by means of a float 55 controlling a supply valve in the inlet structure 56.

In order to guard the inlet ends of 45 passages 15 and tube 34, I surround them by a screen 61.

I claim as my invention:

1. In a carbureter, the combination with a main body having a mixture outlet, a fuel reservoir, a primary carbureting unit comprising a fuel nozzle and an air inlet passage delivering to the mixture outlet, and one or more supplemental carbureting units each comprising a supplemental air inlet passage, a mixture passage delivering to the 55 mixture passage of the main body, a valve arranged between the supplemental air inlet and the adjacent mixture chamber, a fuel nozzle having its discharge end in the supplemental air inlet passage materially above 60 the normal fuel level in the main body and above the fuel nozzle of the primary carbureter unit and its receiving end connected to the fuel reservoir by a capillary tube, and an

independently adjustable spring acting to normally hold the valve closed. 65

2. In a carbureter, the combination with a main body having a mixture outlet, a fuel reservoir, a primary carbureting unit comprising a fuel nozzle and an air inlet passage delivering to the mixture outlet, and one or more supplemental carbureting units each comprising a supplemental air inlet passage, a mixture passage delivering to the mixture passage of the main body, a valve arranged between the supplemental air inlet and the adjacent mixture chamber, a fuel nozzle having its discharge end in the supplemental air inlet passage materially above the normal fuel level in the main body and above the fuel nozzle of the primary carbureter unit and its receiving end connected to the fuel reservoir, means being provided for maintaining the normal fuel level in the supplemental fuel nozzle higher than that in the fuel nozzle of the primary carbureter unit, and an independently adjustable spring acting to normally hold the valve closed. 75 80 85

3. A carbureter comprising a main body having a mixture chamber and outlet, a secondary valve-controlled air inlet, a primary air inlet, and one or more supplemental mixture inlets discharging into the main mixture chamber and each provided with a supplemental air inlet; a fuel reservoir carried by the main body; a primary fuel nozzle communicating with the fuel reservoir and arranged in the primary air inlet; a supplemental fuel nozzle arranged in each supplemental air inlet materially above the normal fuel level in the main body and above the primary fuel nozzle and communicating with the fuel reservoir, means being provided for maintaining the normal fuel level in the supplemental fuel nozzle higher than that in the primary fuel nozzle; a valve arranged between each supplemental air inlet and the communicating supplemental mixture inlet, and a spring normally holding said valve to its seat. 100 105 110

4. A carbureter comprising a main body having a mixture chamber and outlet, a primary air inlet, and one or more supplemental mixture inlets discharging into the main mixture chamber and each provided with a supplemental air inlet; a fuel reservoir carried by the main body; a primary fuel nozzle communicating with the fuel reservoir and arranged in the primary air inlet; a supplemental fuel nozzle arranged in each supplemental air inlet materially above the normal fuel level in the main body and above the primary fuel nozzle and communicating with the fuel reservoir, means being provided for maintaining the normal fuel level in the supplemental fuel nozzle higher than that in the primary fuel nozzle; 115 120 125

- a valve arranged between each supplemental air inlet and the communicating supplemental mixture inlet, and a spring normally holding said valve to its seat.
5. A carbureter comprising a main body having a main mixture chamber and outlet, a depending tubular stem arranged in substantial alinement with said main mixture chamber in communication therewith and forming a primary air inlet, and one or more supplemental mixture passages each communicating with the main mixture chamber and each communicating with a supplemental air inlet; a fuel reservoir 10 sleeved over the depending tubular stem; a primary fuel nozzle arranged in the primary air inlet and communicating with the fuel reservoir; one or more supplemental fuel nozzles each arranged in a supplemental air inlet at a point higher than the primary fuel nozzle and communicating with the fuel reservoir, means being provided for maintaining the normal fuel level in said supplemental fuel nozzles higher than that in said primary fuel nozzle; one or more valves each arranged to normally close communication between a supplemental air inlet and the connected supplemental mixture passage; one or more springs each acting upon one of said valves to normally close the same, and an independently adjustable abutment for each of said springs.
6. A carbureter comprising a main body having a main mixture chamber and outlet, a tubular stem arranged in substantial alinement with said main mixture chamber in communication therewith and forming a primary air inlet, and one or more supplemental mixture passages each communicating with the main mixture chamber and each communicating with a supplemental air inlet; a fuel reservoir; a primary fuel nozzle arranged in the primary air inlet and communicating with the fuel reservoir; one or more supplemental fuel nozzles each arranged in a supplemental air inlet over the fuel reservoir and at a higher level than the primary fuel nozzle and communicating with the fuel reservoir through a capillary tube; one or more valves each arranged to normally close communication between a supplemental air inlet and the connected supplemental mixture passage; one or more springs each acting upon one of said valves to normally close the same, and an independently adjustable abutment for each of said springs.
7. A carbureter comprising a main body having a main mixture chamber and outlet, a depending tubular stem arranged in substantial alinement with said main mixture chamber in communication therewith and forming a primary air inlet, and one or more supplemental mixture passages each communicating with the main mixture
- chamber and each communicating with a supplemental air inlet; a fuel reservoir sleeved over the depending tubular stem; a primary fuel nozzle arranged in the primary air inlet and communicating with the fuel reservoir; one or more supplemental fuel nozzles each arranged in a supplemental air inlet at a point higher than the primary fuel nozzle and communicating with the fuel reservoir, means being provided for maintaining the normal fuel level in said supplemental fuel nozzles higher than that in said primary fuel nozzle; one or more valves each arranged to normally close communication between a supplemental air inlet and the connected supplemental mixture passage; one or more springs each acting upon one of said valves to normally close the same, and an independently adjustable abutment for each of said springs.
8. A carbureter comprising a main body having a main mixture chamber and outlet, a tubular stem arranged in substantial alinement with said main mixture chamber in communication therewith and forming a primary air inlet, and one or more supplemental mixture passages each communicating with the main mixture chamber and each communicating with a supplemental air inlet; a fuel reservoir; a primary fuel nozzle arranged in the primary air inlet and communicating with the fuel reservoir; one or more supplemental fuel nozzles each arranged in a supplemental air inlet at a point higher than the primary fuel nozzle and communicating with the fuel reservoir, means being provided for maintaining the normal fuel level in said supplemental fuel nozzles higher than that in said primary fuel nozzle; one or more valves each arranged to normally close communication between a supplemental air inlet and the connected supplemental mixture passage; one or more springs each acting upon one of said valves to normally close the same, and an independently adjustable abutment for each of said springs.
9. In a carbureter, the combination of a main body having a mixture outlet, a fuel reservoir, a primary carbureting unit comprising a fuel nozzle and an air inlet passage delivering to the mixture outlet, and a plurality of supplemental carbureter units each comprising an air inlet passage, a mixture passage delivering to the mixture outlet of the main body, a valve arranged between the supplemental air inlet and the adjacent mixture passage, a fuel nozzle having its discharge end in the supplemental air inlet passage at a level materially above the fuel level in the reservoir and the fuel nozzle of the primary carbureter unit and its receiving end connected to the fuel reservoir

4
by a capillary tube, and an adjustable spring acting to hold the valve closed, the springs of the several supplemental carbureter units being adjusted so that their associated valves

5 require different suctions to open them.

In witness whereof, I, have hereunto set my hand and seal at Indianapolis, Indiana,

this 18th day of March, A. D. one thousand nine hundred and twelve.

GEORGE M. SCHEBLER. [L. S.]
